Application March 18, 1933, Serial No. 599,623

11 Claims. (CL 208—181)

The present invention relates broadly to the recovery of precious metals from their ores, and while certain salient features of the invention are applicable to a wide variety of methods for separation the invention relates particularly to amalgamation with the aid of electrical and magnetic influences.

Even the amalgamation of coarse and relatively clean gold, for example has presented many difficulties heretofore, particularly insofar as high recovery is concerned, while the recovery of finely divided and encrusted gold has presented problems heretofore unsolved insofar as actual commercial results are concerned.

As above implied, the primary object of this invention is the provision of efficient, commercially practicable high recovery of finely divided gold and other metals as well as the equally efficient separation of gold, silver, mercury, etc., from foreign accumulations and incrustations.

The recovery of finely divided precious metals occurring in alluvial deposits; or mixed with oxidized metals and cyanides; or occurring as unrecovered values in tailings from old workings; 25 or after having passed ordinary separators and amalgamators, has continually attracted the attention of miners and investigators while heretofore about the only reasonable degree of success has been had by resorting to electrolytic and like 30 methods by employing the direct current between an anode and a cathode between which the ore is passed.

The electric current is employed on the theory that gold will be driven by the direct current toward and into contact with mercury carried on the cathode, whereupon natural amalgamation takes place. If the operating conditions are ideal and the mercury remains uncontaminated, then recovery is good but these ideal conditions 40 seldom exist and usually "sick quick" results in an operating expense which is not suitably offset by the degree of recovery.

Again in the use of electrolytic separators various devices are resorted to for activating the 45 mercury or adding sodium amalgam continually to the plates, but again even with such care colloidal clays and the like hold the desired metal so strongly that the pulp must consist of large percentages of water while same is run at relatively 50 slow speeds over the plates.

An important object of my invention is the provision of means whereby unusual molecular or atomic activity is set up within the metal to a degree which causes it to become isolated and

freed of coatings which would otherwise interfere with rapid amalgamation.

Another and important object of the invention is to provide in an amalgamator for the constant activation of the quicksilver so that contaminating matter is broken down, driven from, and otherwise prevented from compounding with, the mercury and the amalgam of mercury and the metal sought after.

In the prior art it is common to depend upon the same direct current intended to drive the gold to the amalgam, to also act to keep the mercury from fouling; this method however being undependable. Another method known to the prior art is that of feeding to the amalgam plates a continuous fresh supply of mercury which has been treated with sodium or the like; this method being quite expensive and requiring constant attention on the operators part.

In the present invention the introduction of sodium amalgam or the like is not required; the mercury is activated and kept in proper condition by means operating simultaneously with the recovery and at substantially the same point so that all steps are carried out at the same time without complicated apparatus.

In this connection it is another object of the invention to provide for simplicity of apparatus, low first cost, and low operating cost and superintendence by providing an amalgamator in which many of the parts serve dual or multiple functions.

Expressed in other words; it is among the objects of this invention to provide an amalgamator which is highly efficient, capable of handling relatively thick pulps, and which in one general type, size and design is suited to a wide variety of operating conditions merely by slight adjustments and without the exercise of more than ordinary skill upon the part of the operator.

Perhaps one of the greatest limiting factors in all amalgamation work is the limited surface area which a body of mercury presents to the passing metals.

It is therefore another and important object of the invention to provide for greatly multiplying the actual exposed surface of mercury and without employing any unusual amounts and while keeping the mercury in pools of such depth that clean-ups are not frequent. The present invention actually provides for moving the pulp at a rapid rate of flow over a plate of limited area while the mercury is actually caused to "dance" upon the plates and be hurled vertically into the passing pulp in fine globules and attenuated fine

gers which together present a greatly multiplied and extended surface reaching like a net work thru the mass of rapidly moving pulp; and this of course without loss or "flouring" of the mercury.

While in the prior art agitation is employed in amalgamators such is a physical agitation promoted solely to jig heavy particles of sand and ore and prevent clogging of the plates.

10 It is another object of this invention to provide a new and different type of agitation or vibration to the amalgam plates so that in addition to dislodging heavy particles it promotes, or aids in promoting the desired attenuation of the mercury surface. Also it is thought that the motion imparted to the mercury by features of this invention helps in keeping the mercury free of films and furthers certain electrical and magnetic influences which are brought to bear upon the 20 mercury mass.

Still another object of, and result had by, my invention is the retention of mercury to defined paths of movement so that even while it dances upon the vibrating plates it will not be washed away by heavy pulps and rapid flows, and in the case of riffles the original charge placed in each riffle pocket will remain. Obviously it is the provision of this feature that adds to the possible thickness of pulp and rapidity of flow conducive to high values obtained in a given period from a 30 plate of given area.

In my improved amalgamator about to be described the construction and operation made possible by this invention is so simple that it becomes at once commercially practicable to move the machine direct to the isolated locations where extremely low grade ores and alluvial deposits may be profitably treated.

The salient steps made possible by and included in my invention will now be given:—

40 One such step and the first is that of mixing the ore, tailings, silt or the like to form the pulp which is then passed over a riffle plate containing mercury in each pocket. The plate serves as an electrode while other electrodes contact with the water of the pulp and close a circuit sending low voltage alternating current thru the pulp. This passage of alternating current is believed to set up a condition in the gold or other metal 45 to be recovered which causes each particle and molecule of the metal to become an isolated whirling mass separated from its previous incrustations and in proper condition for amalgamation. It also appears that the condition of the 50 metal product by this alternating current renders the metal more susceptible to being effected in the desired manner by other forces which are brought to bear upon it as described in the next step.

55 Co-incident with the passage of the alternating current thru the flowing pulp, lines of force from a magnetic field of alternating current type are set up substantially normal to the plates and the body of mercury in each riffle pocket.

60 This is done by the provision of alternating current energized electro-magnets arranged below each of certain riffle pockets so that the flux is from one set of poles normally upward thru the plate and then down to the other poles and reverse. The body of mercury in each pocket over the magnet poles becomes a shorted secondary for the flux and of course certain currents are thereby set up in the mercury mass.

To attempt to explain, in the light of present 75 day understanding of electrical and magnetic phe-

nomena, the combined action of the low voltage charge passing from electrode to the plate, and the action of the low voltage current and the magnetic flux combined, is venturing upon disputed hypotheses.

80 Seeing is believing, however, and in actual observation of my improved amalgamator it is seen during operation that rapid flow of pulp does not dislodge the mercury; the mercury shows the brightness and mobility ascribed by skilled persons to the most efficient form of amalgamation; the mercury sends out fingers into the flowing mass pulling the gold back to the plates; and after a long run it is seen that the plates still contain the original amount of quick, while of course retorting shows the final proof of the machine's efficiency.

85 It should be explained at this point that by means of iron plates secured to the underside of the plate in suitable relation to certain poles of the magnets, said magnets provide the desired physical vibration of the plate as well as the more mysterious effects upon the mercury and recoverable metals.

90 In the accompanying drawings I have shown 100 one practical embodiment of my invention; same being in the form of an amalgamator having all the features and advantages of my invention as well as the features of advantage of the riffle and jig combined.

95 In the said drawings:

Figure 1 is a plan view of the amalgamator, parts being shown broken away to reveal underlying parts.

Figure 2 is a vertical section thereof.

Figure 3 is a fragmentary longitudinal section thereof.

105 Specifically; the numeral 4 indicates a copper riffle plate of the stepped type and suitably inclined as a whole for the gravity flow of pulp 115 from the apron 5 at the upper end to a trough 6 and spill 7 respectively positioned at the lower end.

110 Each of the indentations or pockets 8 of the riffle plate is partially filled with mercury as at 9 so 120 that the entire surface of the plate is not covered with mercury. It is sufficient that the mercury employed be commercially pure and otherwise untreated.

125 The plate is of such thickness for its width and length that it is capable of acting as a drum head and capable of vibration at low pitch to produce tympanitic resonance. This term is employed in contradistinction to the ordinary vibration of a Jig or the like; it being understood that 130 the copper itself vibrates and not the entire assembly.

135 Accordingly the plate is held securely by two relatively non-vibratory parallel side frame members 10, 10; each of which is bisected longitudinally along a line 11 conforming to the surface contours of the riffle plate. These bisected parts of each side member are clamped again to each other by thru bolts 12, 12 after the corresponding end of the plate has been placed between them.

140 On certain of the riffle steps on the underside of the plate iron plates 14, 14 of limited area are suitably secured.

145 Above the riffle plate I provide a grid composed of two parallel side members 16, 16 and connecting cross bars 17, 17; the members 16, 16 being just above and parallel to the corresponding one of the side members 10, 10, while each cross bar extends from member 16 to the other member 16 parallelly above a corresponding riffle 150

pocket; there being one such bar for each of several rifle pockets.

The grid is adjustably supported above the members 10, 10 by springs 19, 19 one around each of four studs 20, 20 rising from the side members 10, 10. Each member 16 at each end is provided with a corresponding bore 21 receiving the corresponding of studs 20, 20. A nut 22 on each stud is threaded for vertical movement on the stud to provide for adjustment of elevation of each end of each of members 16, 16 so that the grid as a whole may be accurately adjusted and leveled with respect to the rifle plate.

The frame members 10, 10 of the rifle plate are of course die-electric and may be made from timber. A swinging gate electrode 23 is hung one on each of the cross bars of the grid and normally hangs down into the corresponding rifle pocket without touching the rifle plate. These electrodes swing freely so that passing water striking a bent lower edge thereof as at 24 will swing the gate forwardly, elevating this end so that it rides upon the passing water current while establishing physical and electric contact therewith.

The rifle plate is provided with a terminal 25 from which an alternating current lead 27 extends, while the grid is provided at 26 with another terminal from which a second lead 27 extends. These leads are connected, it is understood, but not so shown, to any suitable source of alternating current, preferably low and economical voltage. When the circuit is closed by passing water, current surges from electrode to rifle plate thru the water.

Below each set of iron plates 14, 14 I provide an alternating current electromagnet generally indicated at 29 and comprising an elongated winding 30 and a plurality of spaced laminated cores 31, 31 etc. Each core is of double-U form providing two outside poles 32, 32, etc., and one double width inside or central pole 33, 33. Each half of the central poles is of course complementary to the adjacent outer pole. The central poles are arranged side-by-side suitably spaced transversely across the underside of alternate rifle pockets so that each set of central poles 33, 33 is immediately below a corresponding iron plate 14. The upper terminations of each pole as at 14a are inclined according to the inclination of overlying parts of the plate.

Each magnet is fixed as at 35 to a co-extensive underlying board 36. These boards are each suspended below the plate by depending studs 37 carried by lugs 38 projecting from the frame members 10, 10 below the rifle plate. Strong springs 39 surrounding each stud hold the boards firmly down against nuts 40, 40; one on each stud. Thus the magnets as a whole and their poles may be accurately adjusted in proper spaced relationship to the iron plates 14, 14. These springs are strong enough to prevent appreciable vibration of the magnets and boards so that when the magnets are energized with alternating current the poles impart characteristic alternating current vibration to the iron plates 14 and the attached rifle plate, while the magnets themselves do not move appreciably. Each magnet winding or coil is provided with leads 41, 41.

Now in actual operation I have found that 6 volts or less of alternating current of 60 cycles or less is sufficient for the gate electrodes, while the magnets in practice are wound to give results at 110 volts alternating current, 60 or less

cycles. In actual practice I supply both currents from the same source such as a portable low cycle generator (not shown) or from a 110 volt power line; the 110 volt current being stepped-down to low voltage by a suitable transformer, not shown, for electrodes.

The provision of the required currents and the leads and manner of connecting same is all obvious to those skilled in the art as is also the fact that since I have four magnets in the machine shown they may be connected to receive, for example, 110 volts, or 220 volts, or 440 volts from a line of any one of said voltages.

The method for operating the machine is equally as simple as the machine itself. First the riffles are charged with the mercury as explained before and the current circuits closed. Now the ore, mixed with water and known as pulp is introduced by suitable means (not shown) to the apron at the head of the plate, whereupon it flows down the incline dropping from rifle to rifle. High recovery is the result and after a run of suitable duration the water is drained off and the plates are scraped to remove the rich amalgam.

As to results obtained and actually observable to determine the operating efficiency: When the magnets are energized it is observed that while the mercury undergoes its peculiar motion it shows a very decided tendency to remain in the riffles notwithstanding the force of the flowing pulp trying to dislodge it. The plate may be caused to vibrate audibly and the mercury is seen to be violently agitated while at all times maintaining that bright and mobile character which experienced persons immediately recognize as indicative of maximum amalgamating power.

Even without the use of the low voltage and the electrodes, the machine provides an improved amalgamator for those metals and forms of metal which are recoverable by ordinary amalgamation; this by reason of the peculiar agitation imparted to the mercury by the magnets, together with the increased effective surface so provided, and by reason of the mechanical action of the mercury tending to prevent film formations on its surface.

For the more effective recovery of finer forms of metal the electrodes are essential and their efficiency, or at least the efficiency of the machine as a whole is undoubtedly due to the combined effect of the electrodes current and the magnetic flux co-operating, even apart from the movement of the mercury.

The machine and methods above described are applicable to the recovery of silver, mercury and other metals as well as gold and those skilled in the art will understand that for any given metal there is an ideal combination of voltages, cycles of alternation, rate of the plate vibration etc. Also selective recovery will be possible to those skilled in the art so that successive recoveries may be had such as largely gold in certain riffles, silver in others and so on thru the electromotive series of the metals.

Where mercury occurs in the ore native or in such combinations as are readily broken down by the machine, then in the trough additional mercury will be found at the end of a run.

The rapid vibration of the plate is observed to prevent sand and heavy particles from accumulating on the riffles and while magnetic iron not previously separated will tend to remain in the magnetic fields the velocity of the passing pulp will periodically dislodge it, with the result

that it passes on while the mercury still remains.

Now it is to be understood that amalgamators, riffles, launders, jigs, concentrators and like mining equipment are to a great extent analogous and interchangeable in function, and the foregoing disclosure and my invention will immediately suggest to the skilled mind various allied uses to which my complete machine and operative combinations of parts thereof may be put.

For example, without the electrodes and without flowing pulp, the machine by reason of agitation and vibration and magnetic flux will serve as a concentrator in both wet and dry processes and in certain flotation cases. Also it is ideal for jiggling of any sort.

Without the use of the electromagnets the arrangement of riffles and electrodes provides results comparable with many ordinary electrolytic machines and with less power consumption and less resistance to flow; this by reason of the disposition of the gate electrodes with respect to the riffle packets; and of course it is applicable in this manner to direct current. While the machine may be used in this manner a comparison of the results had with and without the use of the alternating current magnets is convincing.

In summarizing the functions of the various parts of the machine: The mercury in itself, aside from its usual functions shorts the magnetic flux and reduces the power consumed by the magnets. The swinging electrodes provide a constant and uniform contact with the flowing pulp at all times and are particularly active over those areas of the plate where the magnetic forces are less pronounced and where the plates contain little or no quick; thereby co-operating with the magnets a further degree by fully utilizing all exposed surfaces of the plate. The functions of the magnets are manifold and include; high frequency short length mechanical vibration for the plate; vibration of the plate in the audible range; variable rates of vibration according to the cycles of alternation of the current used; agitating the plate proper for reducing the friction between the plates and heavy solids so that sand clogging and the like does not take place; physically agitating the mercury so that it presents new surfaces and greatly multiplied surface to the pulp at all times; physically agitating the mercury so that impurities and rejected films of material are readily disposed of by the flowing pulp; hurling the mercury to appreciable elevations in the pulp so that the mercury goes "halfway" in meeting the gold; holding the peculiarly moving mercury to defined lines of travel; setting up currents in the mercury which are believed to help in keeping the mercury activated; increasing the effective gravity of the metals to be recovered; and in various ways co-operating with the current from the electrodes to further promote amalgamation.

All of these effects which are new or heretofore unused in recovery methods I deem to belong to my invention and it is understood that any machines, devices or combinations of parts set forth in the appended claims producing these heretofore unapplied phenomena are within the scope of the invention.

I claim:

1. In an amalgamator, a vibratory magnetically influenced plate provided with mercury-containing pockets, and alternating-current-energized magnets below said plate having opposed poles disposed each below a corresponding pocket, a lead connected to said plate, electrodes dis-

posed to float on water passing over said plate, a lead for said electrodes and means for supplying said leads with current.

2. In an amalgamator, a vibratory magnetically influenced plate provided with mercury containing pockets, alternating-current-energized magnets below said plate having opposed poles spaced apart under said plate, a lead connected to said plate, electrodes; one above each pocket disposed to float on water passing over said plate, a lead for said electrodes, and means for supplying alternating current to said leads.

3. In an amalgamator, a vibratory plate provided with spaced mercury containing pockets, alternating-current-electro-magnetic-means for vibrating said plate; said means having opposed poles each below a corresponding pocket, and paramagnetic elements, one for each of said poles, secured to said plate immediately adjacent the corresponding pole; said elements spaced apart whereby the mercury contained in said pockets acts to short the lines of force passing from pole to pole of said magnetic means.

4. The amalgamator as in claim 3 and further including; means for flowing pulp over said pockets, electrodes; one for and above each pocket to make contact with flowing pulp.

5. In an amalgamator, a relatively non-magnetic plate provided with a pair of spaced mercury-containing pockets, an alternating-current-energized electro-magnet below said pocket having opposed poles; one under each pocket, and a winding passing between said poles; the windings being elongated with the major extents paralleling corresponding pockets; each pocket being elongated.

6. The amalgamator as in claim 5 and further including means for supplying alternating current to said windings, and electrodes; one for and above each pocket disposed to contact with water flowing over said plate; said electrodes connected with said means.

7. The amalgamator as in claim 5 and further including means on said plate strongly attracted by said magnet, means for supplying alternating current to said windings, and electrodes one for and above each pocket disposed to contact with water passing over said plate; said means connected for also supplying current to said electrodes.

8. In an amalgamator, a metal plate declined forwardly, a rigid dielectric frame holding said plate at its sides whereby intermediate parts of the plate may be vibrated; said plate formed with a succession of steps having portions forwardly inclined and other portions substantially vertical to provide a series of pockets each of which is of decreasing depth forwardly, a pulp feeding apron at the upper end of said plate, a grid supported above said plate by said dielectric frame members, swinging electrodes on said grid one for and depending into each pocket without touching said plate, a terminal on said grid, a corresponding terminal on said plate.

9. The amalgamator as in claim 8 and further including electromagnets fixed under said plate having a plurality of poles; the poles of said magnets being opposed longitudinally of the plate and aligned below corresponding of the pockets, iron plates attached to said inclined plate above certain of said poles, and means for energizing said magnets and said electrodes with alternating current.

10. In a separator, a non-magnetic riffle plate providing settling pockets for heavy metals,

means for flowing pulp over said pockets, spaced pairs of poles below said plate, windings, one for and around each pair of poles, means for supplying alternating current thru said windings; said 5 poles of each pair spaced apart at the ends adjacent said plate and each pole of a pair being slightly spaced from said plate whereby the plate and pulp form the sole adjacent flux-shortening body between the poles.

10

11. The separator as in claim 10 and further including an individual paramagnetic member for each pole secured to said plate immediately above the pole; each paramagnetic member well spaced from all other members. 80
